PUNCHING MACHINE

Robert L. Houston, New York, and Robert E. Smith, Mount Vernon, N. Y., assignors to International Business Machines Corporation, New York, N. Y., a corporation of New York

Application October 3, 1945, Serial No. 620,040

16 Claims. (Cl. 164—113)

1

This invention relates to punching and printing machines and more particularly to the type in which the data to be punched is controlled and determined by keys and is punched on a tape so as to provide a punched record of the items, totals and other transactions entered in the machine.

While some or all of the features of the present invention may be incorporated in adding machines of a type other than that identified and the punch arrangement may punch on other forms of records such as individual cards, etc. the punched and printed tape produced by the illustrative machine is particularly useful to provide a sequentially punched and printed record of the transactions. In one use of the punched part of the tape, the latter may subsequently be utilized to segregate items of different classes or to use the punched tape differently the punched tape may be converted to a punched card record to control present card controlled machines. The present machine coordinates the punched data with the printed record customarily made by the adding-listing machine so that obviously the interpretation of the punched data exists without requiring interpretation by a separate machine operation.

It is, therefore, the main object of the present invention to incorporate in an adding-listing printing machine a tape punching mechanism which provides for conjoint punching-printing of the numeral data in a linear cooperative relationship and in a manner which conserves the record material on which punching-printing is effected.

A still further object of the invention is to provide a punching mechanism which is conditioned simultaneously with the printing mechanism of the adding-listing machine and then actuated to punch the data in a linear relationship with respect to the printed data.

Another object of the invention is to provide a novel form of punching mechanism which will punch character representations by coded holes on a record which requires substantially no more space vertically on a line of the sheet than a corresponding line of the printed data.

Another object of the invention relates to the coding to carry out the preceding object which provides for representation of the characters by apertures selectively located at four index point or code positions, such code positions being preferably within the area permitted by the vertical line spacing. More specifically, four equally spaced index point positions within the vertical rectangular area provided by line spacing the

2

sheet provide such code positions and by variously arranging the holes according to a predetermined code the different numerical characters may be represented.

5 Many benefits are derived by arranging the punched character representations in this manner, among which it may be stated that the punched data is arranged on the same line as the corresponding printed data and occupies substantially no more vertical line space than the printed data. Further, the same line spacing mechanism may provide the same extent of separation between the successive lines of punched data as the successive lines of printed data. This provides for economical use of the record material and without necessitating any changes in the line spacing mechanism of the existing machine.

With regard to the punching mechanism, an 10 object of the invention is to provide a form of punch selecting mechanism which is capable of being attached to existing adding-listing machines without a reconstruction of the basic machine, such attachment enabling the basic 15 functions of the machine to be performed and jointly carried out with the data punching operations.

20 More specifically it is an object of the invention to provide electrical timing switches operable by the conventional differential stop mechanism of the key controlled adding-listing machine to control by electrical instrumentalities the differential position of punch selecting bars.

Another feature of the invention relates to the 25 provision of automatic means to effect suppression of punching zero representations at the left of the significant digit of highest denominational order and to condition the punch selecting mechanism to cause such zero representations to be made in all zero representing 30 orders which are at the right thereof.

Another feature of the invention relates to the provision of means to punch the tape or other record material to represent certain additional functions which may be selectively carried out by the operator in the basic adding-listing machine, such as non-add operations, subtraction operations, printing of totals and sub-totals, etc.

35 The preceding object of the invention, viz., the capability of perforating the tape to represent symbolic printed data is also carried out in a manner which enables the control for the symbol punching bar to be provided by a simple attachment to existing machines.

40 More specifically in the basic type of machine

50

55

in which the present improvements are incorporated, conditioning of the machine by the operator for effecting these additional functions sets a symbol printing bar prior to an operating cycle of the machine. In the present machine by a simple attachment the differential setting of the symbol punching bar is controlled by the position of such symbol printing bar.

As the invention is subsequently disclosed and understood, it will be apparent that many or all of the features of the present invention may be incorporated in other forms of machines. It is, therefore, to be understood that the basic machine identified herein is merely illustrative and not restrictive.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a transverse sectional view taken at the left side of the machine and shows particularly the manner in which the customary differential stop mechanism controlled by the keyboard controls the setting of the punch selecting bars.

Fig. 2 is a plan view of the machine with the cabinet broken away to show the interior parts comprising the present invention.

Fig. 3 is a sectional view taken at the left side of the machine showing certain cam operated connections for operating parts comprising the present invention.

Fig. 4 is a sectional view taken on the line 4—4 of Fig. 1, the mechanism illustrated in this figure comprising the zero eliminating and zero insertion mechanism.

Fig. 5 is a detail sectional view taken on the line 5—5 of Fig. 2.

Fig. 6 is a detail sectional view taken on the line 6—6 of Fig. 2.

Fig. 7 is an electrical wiring diagram of the machine.

Fig. 8 is a timing diagram.

Fig. 9 is the diagram illustrating the code for representing numerals and symbols.

Fig. 10 is a fragmentary portion of a tape punched and printed by the present machine illustrating co-linear printing and punching to represent the items entered in the machine or the total recorded by the machine.

For the purposes of illustration the present invention is shown incorporated in the type of adding machine which is known commercially at the present time as "Allen Wales Desk Model," which construction of the machine and operation thereof is well known and is disclosed in issued patents, primarily the patents to H. C. Peters, Nos. 1,386,021 and 1,386,022, both patented August 2, 1921. This type of adding machine is the well known multiple keyboard, single accumulator, listing type, which under control of the keys effects listing of items and the accumulation of items together with total taking means for providing either a sub-total or grand total of the items recorded by the printing mechanism. Also mounted upon the amount keyboard are other manually operated keys or levers for performing special functions in carrying out the work, such as non-add operations, sub-total, grand total, subtraction, etc.

For a detailed disclosure of the basic adding machine reference may be had to the aforemen-

tioned patents but herein a description of the construction and operation of certain parts of the said basic machine involved in the present invention will be explained.

5 The keyboard consists of rows of keys 3 (Figs. 1, 2) which are numbered 1—9, inclusive, there being multiple rows of such keys for denominational entering the items.

10 The motive power of the machine may be derived either by a motor, or as in any manually operated model by a crank handle, and when either form of motive power is utilized, two operating shafts designated 1 and 2 in Fig. 1 are reciprocated, this reciprocation in each operating cycle being designated in the timing diagram of

15 Fig. 8 by the term "Forward" and "Return," corresponding to the forward movement of the crank handle and the return movement of the crank handle as in manually operated machines.

20 Shafts 1 and 2 herein conform respectively to shafts 200 and 204 in Patent No. 1,386,021 and it is to be understood that herein the shafts 1, 2, are interconnected as in said patent to be concurrently rocked. It is because shafts 1 and 2 are

25 provided with supplemental cams to effect operation of certain parts involved in the present invention that they are especially referred to. These operations will be described as they are encountered in the specification.

In Fig. 1 reference numeral 40 designates a stop bar similarly designated in Patent No. 1,386,021, said stop bar being provided with differentially disposed stop portions 40a which are adapted to contact with the stems 4 of the depressed keys,

30 the stop bar 40 for each row of keys having a forward and return movement effected by the operation of the main operating mechanism of the adding machine to thereby project during the forward movement one of said stop portions 40a against the stem 4 of the key depressed in that row, thus enabling the stop bar to advance a distance proportional to the value of the key depressed.

35 However, if no key should be depressed in a row the forward movement of the stop bar 40 will be limited by the coaction of the most forward stop portion 40b with a stop member 32b which represents the zero position of the stop bar 40, all of which is fully described in Patent No. 1,386,021.

40 The printing mechanism of the illustrated machine comprises a group of numeral printing type bars 50 (Fig. 2), generally one for each order of the accumulator. The movement of the type bars 50, as fully explained in Patent No. 1,386,021,

45 is under control of the stop bars 40 and it is understood that the differential movement of the latter is determined by the depressed keys. The specific means to effect the setting of the type bars 50 does not form any part of this invention since it is fully described in Patent No. 1,386,021.

50 Herein associated with the punch selecting bars 137 (Fig. 1) is a differentially actuated electrical timing mechanism which is adapted to control the differential positioning of punch selecting bars 137, such mechanism shown herein comprising a form which is readily attachable to an existing machine of the illustrative type.

55 Attached to the stop bar 40 for each denominational order is a switch closing member 108 which also moves forwardly a distance proportional to the key depressed. A transverse plate 105 is adapted to have its extremities fit in slots 105a in the side frames of the machine so that said support member 105 may be forwardly and rear-

60 wardly reciprocated. The support plate 105 car-

ries a plurality of contacts comprising switch blades 106, 107, each upper switch blade having a cam projection 107b in the plane of the switch closing member 108 of the same order. Secured to the main drive shaft 1 is a cam plate 101 (Fig. 1) coacting with a follower roller 102a carried by the upper arm of a double arm 102 pivoted at 102b. The lower arm of double arm 102 has a link connection 103 to the lower arm of a double arm 104 pivoted at 104a and which has a finger 104b extending into a hole in the support member 105. This mechanism may be duplicated for each end of the support member 105 to provide an equal and simultaneous forward and rearward movement at the extremities of the support plate 105. The configuration of the cam 101 is such that it will effect a movement of the support plate 105 forwardly substantially synchronous with the movement of the stop bars 40 effected by the operating mechanism of the patented machine, but when the stop bars 40 are moved to differential positions and then stopped, cam 101 is adapted to move the support plate 105 and the switch blades 106, 107 carried thereby a complete forward movement and a return movement. Obviously, the over-movement of switch blades 106 and 107 forwardly after a stop bar 40 has been stopped at its differential position will cause the projection 107b to cam contact plate 107 as it rides by the now stationary switching member 108 thus depressing contact blade 107 to close the related contacts 106, 107. This closure will energize a related punch selecting circuit at differential times to stop the upward synchronous movement of the related punch selecting bar 137.

It is, of course, desirable that electrical connections be made to the contact blades 106, 107 during their forward and return movement and this can be provided by suitable pigtail wire connections thereto. Preferably, however, this is secured by having integral extensions 106c (Figs. 1 and 7) of the contact blades 106 slide over associated contact plates 106a. As will be obvious from the wiring diagram (Fig. 7) each contact blade extension 106c makes a continuous electrical contact with the associated contact plate 106a. The series of contact plates 106a are carried by a fixed support bar 109 of insulating material.

From the wiring diagram (Fig. 7) it will be evident that all of the contact blades 107 are commonly connected by a wire 110 and said wire is connected to contact blade extension 107c of highest order which has a sliding connection to a special contact plate 106aa also carried by support bar 109. Special contact plate 106aa has a circuit connection to main circuit closing contacts 156, 157 to be later described.

A group of punch selecting bars 137 is mounted at the left of the customary type bars 50 as shown in Fig. 2. For each numeral printing type bar 50 there is provided a corresponding punch selecting bar 137 so that each digit of the item or total can also be recorded by punching upon the same tape on which the items and totals are printed. The punch selecting bars 137 are guided for vertical reciprocating movement by comb bars 132 and 133 (Fig. 1) and each bar 137 has at its lower end a slot 137a in which fits a stud 130 secured to the extremity of a lifting arm 128 loosely mounted upon a rod 129. Arm 102 has a link connection 120 to an arm 121 fixed to a rock shaft 122. Fixed to the rock shaft 122 is a pair of arms 123 which are cross-connected by a spring support rod 124.

Springs 127 are extended between the rod 124 and each of the lifting arms 128.

The configuration of the cam 101 is such that it rocks the frame consisting of the side arms 123 and rod 124 to tension the springs 127 and through such tensioned springs rock lifting arms 128 to raise the punch selecting bars 137. Obviously, since cam 101 effects the forward movement of the switch plates 106, 107, the punch selecting bars 137 will be elevated synchronously therewith and by circuit means to be subsequently described the closure of the contacts 106, 107 will energize a punch selecting magnet 170 to terminate the upward movement of the punch selecting bar 137. When such movement has been terminated, the frame 123, 124 will nevertheless complete its upward movement which will result in merely tensioning springs 127.

The differential positioning of the punch selecting bar 137 is preferably controlled by electromagnets 170, one provided for each order. Energization of each electromagnet 170 rocks its bell crank armature 170a and through a link connection 171 rocks the latching member 173. Each latching member 173 normally latches a stop pawl 174 by cooperation with the shoulder 173a and when said stop pawl 174 is unlatched said stop pawl will engage one of the stop notches 131 formed in each punch selecting bar 137. The particular notches 131 which are engaged by the pawl to set the punch selecting bar 137 at the digit positions 1-9 are indicated in Fig. 1. Above the "1" notch 131 there are two notches designated 131a and 131b which pertain to the zero punching mechanism.

A general description of the operation of the arrangement for setting the punch selecting bars 137 will now be given, particularly in connection with Fig. 1, the wiring diagram of Fig. 7, and timing diagram of Fig. 8.

The keys of the keyboard are first depressed in accordance with the value to be recorded by printing and punching and thereafter the main operating mechanism goes through a cycle of operation either by a manual or power operation. At the 4 point in the forward portion of the operating cycle contacts 156, 157 (see Figs. 3 and 7) are closed to provide a current supply. Secured to the operating shaft 2 is a cam 158 (Fig. 3) which rocks a bell crank 155 during a portion of its clockwise movement to close the switch 156, 157 for the duration indicated in Fig. 8. From Fig. 7, it will be seen that closure of such contacts connects a grounded current supply to the special contact plate 106aa. Shortly after contacts 156, 157 are closed, cam 101 (Fig. 1) will cause the positioning of the groups of timing switches 106, 107 forwardly and the punch selecting bars 137 upwardly synchronously. In the illustrative basic machine the stop bars 40 also take positions synchronously with the setting of the type bars 50 (Fig. 2). The switch closing members 108 follow the movement of related timing switches 106 and 107 until such time that one of the stop portions 40a related to the key depressed will abut the stem 4 of such depressed key to terminate the forward movement of the stop bar 40 and the switch closing member 108. The timing switch, however, will continue to move forwardly and the projection 107b of switch blade 107 will ride beneath the now stationary switch closing member 108 to cause the closure of the timing switch 106, 107 at about the time that the punching selecting bar 137 has risen to the corresponding

digit position. For each denominational order a circuit will then be closed from the ground, (Fig. 7) through the battery, through switch 156, 157 now closed, contact plate, 106za, sliding contact member 107c, through the related timing switch 107, 106, the associated sliding contact 106c, contact plate 106a, to the grounded electromagnet 170 to energize the latter. The energization of magnet 170, as previously described, causes stop pawl 174 to be unlatched to engage the particular notch 131 of the punch selecting bar 137 which corresponds in digit designation to the key depressed. The stopping of any punch selecting bar 137 at any digit position above 9 will result in the tensioning of the spring 127 after the bar has been stopped, due to the fact that the frame 123, 124 is given an invariable movement for each machine operation. At point 15 of the forward portion of the cycle (see Fig. 8) all of the punch selecting bars have been moved to their proper digit position and remain in such position from the last described point in the cycle until point 15 of the return portion of the operating cycle. It is during the time that bars 137 remain in upward position that the selected punches are actuated to effect the punching operation by means which will now be described in detail.

The numeral data is represented by holes punched in the tape according to the code shown in Fig. 9. Four code positions numbered 1, 2, 3, 4 are utilized singly or in combination in order that the punched data may be linearly disposed and in horizontal alignment with the line of printed data, as shown in Fig. 10.

It will be observed from Fig. 9 that 0 digit is represented by a single hole at the 1 index point position, the 1 digit by holes at the 1 and 2 index point positions in vertical alignment, digit 2 is represented by holes at 1 and 3 in diagonal alignment, etc. so that by various combinations of holes at these four index point positions the desired digit may be expressed and will satisfy the requirement that the punched data does not greatly exceed the space required for printing the same information and is arranged linearly.

To punch the record strip according to the preferred code, each punch selecting bar is slotted vertically at its upper portion to receive a punch selecting plate 134. Said plate is slidably mounted on the punch selecting bar 137 by means of studs 134a received by guide slots 137b of the punch bar 137. Suitable flat springs 134b retain the punch selecting plate 134 forwardly out of the path of the extremities of punches to enable the free positioning of the punch selecting bar 137. The rear of each punch selecting plate 134 carries integral punch selecting projections 135 which are coded according to the code of Fig. 9 so that at the different digit positions of the punch selecting bar 137 said projections 135 will select punches from the group of four which will punch holes in the record strip conforming to the code of Fig. 9. Cooperating with the punch selecting plate 134 of each denominational order is a punch operating plate 180 (Figs. 1 and 2) and such plate is coextensive with the group of punch selecting bars 137 as shown in Fig. 2 and is slidably mounted in a side frame 138 and a bracket 139.

Referring now to Fig. 3, a box cam 140 is secured to the shaft 1 and has contiguous slot formations 140b, 140c which cooperate with a follower roller 141a carried by the lower end of a double arm 141 pivoted at 141b. Said arm 141

has at its upper extremity a link connection 142 to an arm 143 secured to a rock shaft 144, which is also shown in Fig. 2. Referring now to Fig. 1 secured to shaft 144 is an arm 145 having at its extremity a pin 145a cooperating with a vertical slot 180a which is formed in a bracket secured to the punch operating plate 180.

From Fig. 3 it will be seen that the cam slot portion 140b is substantially concentric but the portion 140c is eccentric with respect to shaft 1 so that when roller 141a cooperates with eccentric portion 140c arm 141 will be rocked to rock shaft 144 clockwise, as shown in Fig. 1. Clockwise movement of the arm 145 and pin 145a in conjunction with the vertical slot 180a will effect a camming action on punch plate 180 to move the latter rearwardly of the machine. By its cooperation with the punch selecting plate 134, the punch selecting projections 135 will, according to their differential positions, move punches 191 inwardly against the action of return springs 191c which keep the punches normally out of the way of the tape. The time that the punches 191 are moved rearwardly to perforate the strip is shown in the timing diagram in Fig. 8 wherein it will be seen that the movement is effected while punching selecting bars 137 are maintained in their upward differential positions. The return movement of the cam 140 will reversely actuate the punch plate 180 to restore the latter to its normal position shown in Fig. 1.

The group of four punches for each denominational position is slidably mounted in guide plates 192 and 193 and said punches project through the record strip 204 into a slotted punch die 194. The punches 191 are circular so as to punch round holes in the record strip but the portion 191b of each punch is flattened so that by cooperation with complementary apertured portions of the plate 193 said punches will be prevented from turning in their sockets.

The record strip of the illustrative machine is narrow but of sufficient width to receive printing by the group of type bars 50. The record strip 204 passes over the conventional platen 195 which is line-spaced in the usual manner. In the present machine the record strip is somewhat wider so that the left hand portion (see Fig. 10) may pass in a slot in the punch die 194 and therefore be punched to represent items and totals. The printing line and the punching line are in alignment so that the printed and punched data are linearly arranged as shown in Fig. 10 and the usual line spacing of the record strip 204 to separate the printed data will correspondingly separate the punched data. Due to the preferred code and arrangement of the four punches, the successive lines of punched data receive the same separation as the successive lines of printing.

It is preferable not to depend upon the compression of springs 191c to return the operated punches but to provide means to positively withdraw them from the punched tape. Springs 191c extend between the guide block 192 and turned ends 191a of the punches. A bail 190 is attached to the punch operating plate 180 and its transverse cross member is provided with a horizontal slot through which the forward extremities of the punch pins 191 pass so that said turned ends 191a of the punches are positioned just forward of the cross member of the bail 190. Said cross member cooperates in this manner with the punches of all denominational orders. Obviously, when the bail 190 is restored forwardly after a punching operation, the cross

member of the bail 180 will engage the turned ends 191a of the punches to positively retract punches 191, assisted in this operation by the compression given to springs 191c.

After the completion of the punching operation the punch selecting bars 137 and timing switches 106, 107 are concurrently restored to normal position. This restoring operation begins at point 15 of the return portion of the operating cycle and is effected by the counterclockwise rocking of cam 101. When the roller 102 cooperates with the lower portion of the cam 101 during the clockwise rotation of cam 101, the previously tensioned spring 102c will now, through the intermediate connecting link 103 rock arm 104 counterclockwise to restore timing switches 106, 107 rearwardly. During this return operation stop bars 40 are also being returned to normal position by the operating mechanism of the illustrative machine ahead of the rearward movement of timing switches 106, 107. When switch closing member 108 has been stopped at its normal position (Fig. 1) and the related timing switch 106, 107 is moved rearwardly to its normal position, riding of the cam extension 107b past the switch closing member 108 will again close the timing switch 106, 107 but such closure is ineffective to energize a circuit because at this time the main switch 156, 157 is open. From Fig. 3, it will be seen that when cam 158 returns it rocks pawl 155 idly without closing switch 156, 157.

Of course, the counterclockwise return of the cam 101 will also enable the release of the tension of springs 127 to cause punch selecting bars 137 and attached parts to return to normal position merely effected by the weight of bars 137 and attached parts. However, to positively restore all of the punch selecting bars 137 and not depend upon weight to return them there is pivoted on the arms 123 at 126 a restoring plate 125. Said restoring plate 125 is guided by a bar 125a and its lower edge overlies the arms 128 of all denominational orders. Since plate 125 takes an upward movement commensurate with the frame 123, 124, the upward differential movement of the punch selecting bars 137 is not prevented. Obviously, when said frame 123, 124 is restored the restoring plate 125 will rock all of the arms 128 downwardly, positively forcing all punch selecting bars 137 and attached parts to normal position, as shown in Fig. 1.

Means is also provided to rock stop pawls 174 so as to be relatched by latch members 173. During the clockwise rocking of the cam 140 (Fig. 3) a projection 140a thereof will rock a pawl 151 counterclockwise idly about its pivot on an arm 150. However, when said cam 140 is restored in a counterclockwise direction the projection 140a will strike pawl 151, attempting to rock said pawl clockwise which is frustrated by pin 151a on arm 150. This results in rocking the arm 150 and a rock shaft 152 to which said arm is connected. Secured to the arm 152 are arms 153 which carry a bail plate 154 which, as shown in Fig. 1, is beneath the stop pawls 174. The rocking of the restoring plate 154 upwardly as shown in Fig. 1 at the final operation of the machine (see Fig. 8) will rock all the unlatched pawls 174 to enable their relatching by the latching members 173 which are rocked by springs 175 to effect such function. Springs 175 will, through the connection 171 also rock armature 170a to its normal position.

Eventually projection 140a (Fig. 3) will wipe past the pawl 151 and all of the parts will then

be returned to the normal position as shown in Figs. 1 and 3.

Zero punching mechanism

An additional feature of the machine provides for perforating the record strip or tape to represent intermediate zeros, that is, zeros at the right of the significant digit of the highest denominational order and the suppression of such zero representations for denominational orders to the left of said significant digit. These unwanted zeros are eliminated so as to prevent confusion in interpretation of the record when the record strip or tape is utilized to control a machine.

As previously explained the lowermost zero notch 131b (Fig. 1) is engaged by the stop pawl 174 to set the punch selecting bar 137 to such position that it will select punches to perforate the tape to represent zeros. It will also be recalled that in all orders where a key is not depressed stop bar 40 is moved forwardly so that its most forward projection 40b will engage a stop portion 32b to cause the timing switch 106, 107 of that order to be closed to energize the related stop magnet 170 at a time which causes the stop pawl 174 to engage said notch 131b.

As will be subsequently explained, mechanism is provided to normally prevent the setting of punch selecting bars 137 to zero digit positions in orders which are at the left of the order in which the first significant digit is printed. This mechanism is rendered inoperative for orders to the right of the first significant digit order by the following described mechanism.

Associated with each bar 137 is a member 165 which is pivoted upon a rod 166, said member having a forward tail portion 165c in the path of a stud 136 carried by the related bar 137. Associated with each member 165 is a flat detent spring 167 having an aligning projection selectively cooperating with two notches formed in the related member 165 so as to resiliently hold member 165 in the normal position shown in Fig. 1, or in a counterclockwise rocked position.

Upon the rise of the punching selecting bar 137 of the order in which the highest significant digit 1-9 is recorded, pin 136 will engage the forward tail 165c of member 165 to rock said member counterclockwise to the dotted line position shown in Fig. 1. During such counterclockwise rotation of member 165 its rearward tip of portion 165b passes idly by a related cutout arm 164 and is rocked to the dotted line position. Each higher order member 165 has a laterally extending portion 165a which is normally over the lower horizontal portion 165b of the member 165 of next lower order. Such overlapping of the members 165 (see Fig. 4) enables the member 165 of the first significant digit order to rock the next lower order member 165 and such chain of movement is extended seriatim to the member 165 of lowest denominational order to rock the latter to the dotted line position to abut a restoring arm 222. Thus, in this manner all the members 165 of lower denominational order are set to their counterclockwise rocked position and each out of the range of a plurality of cutout arms 164, thus enabling the punch selecting bar 137 of each order in which a zero is to be punched to be set to zero punch selecting position, as shown by the punched number 5,678.90 in Fig. 10. It will be noted that at the zero position of the punch selecting bar 137 the uppermost code projection 135 is in a position to select a punch to

11

perforate the tape at the 1 code position, according to the code in Fig. 9.

In the return of the punch selecting bars 137 the studs 136 of all orders to the right of the highest significant digit order and including this order will pass by the tails 165c without interference and the punch selecting bars will be positioned to normal at about point 5 of the return portion of the operating cycle (see Fig. 8). Thereafter, mechanism is operative to restore the rocked members 165 which takes place between 4-0 points of the return portion of the cycle.

At the beginning of the forward portion of the operating cycle, cam 215 (Fig. 3) secured to rock shaft 2 will, in the clockwise rocking of shaft 2 enable its high portion to pass downwardly out of engagement with a projection of a bell crank 216 and when such clearance is effected spring 216c will rock bell crank 216 to cause the vertical arm of the latter to abut a fixed stud 216a. During such rocking of bell crank 216 a pawl 217 pivoted on 216 will wipe idly by the projection 218a of a bell crank 218. The rocked position of bell crank 216 is maintained until the 4 point in the return portion of the operating cycle when the counterclockwise restoring direction of cam 215 causes the cam to rock the vertical arm of bell crank 216 to the right, now causing the pawl 217 which is now stopped by the stud 217a to engage the projection 218a and rock the bell crank 218 counterclockwise, shifting link 219 to the left to rock arm 220 and the shaft 221 counterclockwise as viewed in Figs. 1 and 3. Secured to the rock shaft 221 is the restoring arm 222 (Figs. 1, 4) which rocks the member 165 of lowest order and through the overlapping arrangement restores all rocked members 165 to normal position shown in Fig. 1, where they are again resiliently held by detent springs 167.

Eventually, referring to Fig. 3, pawl 217 will wipe past the projection 218a so that the parts 218, 219, 220, 221, and 222 are restored by the spring 218c.

Summarizing, the failure of the depression of a key in each row will cause, through its related differential mechanism, the closure of a timing switch 106, 107 and the energization of stop magnet 170 at a time which will stop punch selecting bar 137 at the zero digit position. The zero inserting mechanism is operative under control of the punch selecting bar 137 used to punch the highest order significant digit to render the normally operative zero punching cutout mechanism inoperative for this order and all orders to the right of the highest significant digit order, so that when zero is to be punched in certain lower orders the punch selecting bars 137 may be adjusted to such zero punch selecting positions.

As previously intimated keys in rows which are at the left of the highest significant digit order are not depressed and the stop bars 40 of such higher orders also go to the zero position. Such higher orders would normally cause the punch selecting bars 137 to be adjusted to zero positions and, if not otherwise prevented unwanted zeros would be punched. The preferred form of mechanism to eliminate such zero punching as in the punched number 34.56 in Fig. 10 consists of the following described mechanism.

In general, for each of the higher orders in which zero punching is to be suppressed the punch selecting bars 137 are depressed to the extent of one tooth space so that the unlatched stop pawl 174 cooperates with notch 131a, at

12

which position the 0 code projection 135 will be below the punches. The bars 137 are depressed prior to the punching operation at point 7 (Fig. 8) in the forward portion of the operating cycle.

Referring to Fig. 3, attached to the drive shaft 1 is a cam 159 having a cam portion 159a cooperating with a follower roller 160b carried by a double arm 160 which has a link connection 161 to an arm 162 secured to rock shaft 168. Rock shaft 168 carries a cutout arm 164 for each order and a single restoring arm 163 associated with the member 165 of highest denominational order. At point 7 in the forward portion of the operating cycle the high portion 159a of cam 159 will rock double arm 160 counterclockwise, drawing link 161 to the right to rock the arm 162 and shaft 168 and all arms 164 counterclockwise. This will cause each zero cutout arm 164 to swing upwardly and by its coaction with the tip of portion 165b each member 165 will rock said member so that the tail 165c which is now just above the stud 136 of punch selecting bar 137 at zero recording position will depress bar 137 so that the previously unlatched stop pawl 174 will engage the tooth 131b. In this manner each of the punch selecting bars is in a position where no zero punching will be made in orders to the left of the highest order significant digit.

At point 13 in the return portion of the operating cycle follower roller 160b (Fig. 3) will now drop to the lower portion of cam 159, enabling spring 160c to rock the parts reversely and arms 163 and 164 clockwise as viewed in Fig. 1. Arm 163 will now press against the portion 165b of the previously rocked member 165 of the highest denominational order and through the overlapping arrangement restores all members 165 previously rocked by the related arms 164 from clockwise rocked position to the normal position shown in Fig. 1, which operation is terminated at point 7 of the return portion of the operating cycle. At such position each member 165 is in the position shown in Fig. 1 and held by the spring detent 167.

45 Punching tape to represent function symbols

The illustrative machine has a printing bar 50a (Figs. 2 and 5) allocated for printing symbols designating certain functions of the machine, such as subtract, non-add, sub-total and total. Inasmuch as these functions are symbolized by printing in the illustrative machine it is also desirable to characterize the punched data by corresponding symbols which are designated in the code of Fig. 9, wherein the uppermost or first symbol represents a subtraction operation, the second a sub-total, the third a total, and the fourth, or lowermost, a non-add operation. The machine is provided with manipulative devices (not shown here) which are set prior to a machine operation to condition the machine for these functions and the depression of each manipulative device directly sets the symbol printing bar 50a to select an associated symbol type for printing. The direct setting means is fully shown and described in the patent to Peters No. 1,386,021, referring particularly to Fig. 15 and associated description.

Referring now to Figs. 2 and 3, attached to a side frame of the machine is a bracket 209 which carries a pivot stud 210a on which is pivoted a double arm 210, the right hand of which extends into a slot in a bracket 213 attached to the top of the symbol type bar 50a so that according to the differential setting of this type bar the double

arm 210 is rocked counterclockwise to cause a contact member 211a pivoted at the other end of said arm to make contact with a contact point 212 so as to bridge the contact point 212 with a common contact plate 212a (see Fig. 7). The contact points 212 are wired to the respective relays 170c (Fig. 7), one side of which is commonly connected so as to extend the energizing circuit through a release magnet 170b to the ground. The common contact plate 212 has a wire connection through switch 156, 157 to the grounded battery. Hence, while the symbol printing bar is set to a certain designating position before the operating cycle of the machine is initiated, and the circuit to a selected relay 170c is completed at one point by the bridging of the related contact point 212 and common plate 212a, said relay is not energized until switch 156, 157 closes at point 4 in the forward portion of the operating cycle in the manner previously described. The relay contacts 170d of said relays 170c are wired to individual contact points 232 to render the associated contact point 232 effective, according to the relay contacts closed. It will be seen that there is a wire connection from one side of each of the relay contacts 170d back to the grounded battery through switch 156 and 157.

The switch points 232 and common contact plate 231 are bridged by a circuit closing member 230 which is carried by and positioned by the plate 105. According to the switch point 232 which has been rendered effective the stop magnet 170 (Figs. 6 and 7) is energized at a differential time, such stop magnet having a function previously described for magnets 170, that is to say, the energization of magnet 170 will stop the symbol punch selecting bar 137a at a differential position so that the punch selecting plate 134 thereof (Fig. 1) will bring coded punch selecting projections 135 in such position as to perforate the tape to represent the function symbols according to the code in Fig. 9.

It was previously stated that energization of the relay 170c upon closure of switch 156, 157 energizes a release magnet 170b. This release magnet, referring to Fig. 6, attracts its armature 171a to rocking latch pawl 172 out of engagement with a notch 131d formed in the bottom of the symbol punch selecting bar 137a. This release magnet normally prevents the rise of this punch selecting bar unless a function symbol is to be perforated on the tape. The circuit for energizing the stop magnet 170a to rock the stop pawl 174 to set the symbol punch selecting bar 137a to a desired position is from the ground, through battery (Fig. 7), switch 156, 157, through the relay contacts 170d of an energized relay, through the effective contact point 232, circuit closing member 230, plate 231, thence through stop magnet 170 to ground. The subsequent opening of the switch 156, 157, of course, deenergizes the selected relay 170c, stop magnet 170 and release magnet 170b, enabling the restoration of the symbol punch selecting bar 137a when the punch selecting bars are restored in the manner previously described. The positioning of the double arm 210 back to the normal position shown in Fig. 5 is effected by its connection to the symbol printing bar 50a when the symbol printing bar 50a is restored to normal by means incorporated in the illustrative machine.

In the exemplary record of Fig. 10 it will be noted that the printed total is shown in the lowest line and at the right the asterisk which

designates the total which is printed by the total printing mechanism. Also at the left it will be observed that perforation of the record strip in the symbol representing column at three coded positions will indicate that the punched data represents a total. Other functions of the machine are similarly designated.

It is pointed out that the operation of the machine for obtaining a total also causes the differential positioning of the stop bars 40 under control of the accumulator to represent such total. The punch selecting bars 137 are set for total representation in the same manner as for item representing operations and the description need not, therefore, be repeated.

While there have been shown and described and pointed out the fundamental novel features of the invention, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a combined printing and punching machine in which a plurality of keys are provided to control the differential setting of a plurality of printing bars to print the data on a horizontal line on a sheet, said sheet being line spaced by a line spacing means, the combination of a plurality of punching bars differentially positioned under control of said keys, coded punch selecting means carried by each of said bars, a group of punches for each bar for punching on the same sheet which is printed in code index point positions arranged within a space substantially equal to the area occupied by each printed digit, said groups of punches arranged horizontally and co-aligned with the printing line and selected for operation by said coded punch selecting means, and a punch die provided with a slot to receive said sheet to enable the latter to receive perforations in horizontal co-alignment with said printed data.

2. In a combined printing and punching machine in which a plurality of keys are provided to control the differential setting of a plurality of printing bars to print the data on a horizontal line on a sheet, said sheet being line spaced by the customary line spacing means, the combination of a plurality of punching bars differentially positioned under control of said keys, coded punch selecting means carried by each of said bars, a group of four punches for each bar and at equidistance corners of an area equivalent to the area of each printed digit, said groups of punches arranged horizontally and aligned with the printing line and selected for operation by said coded punch selecting means, and a punch die provided with slots to receive said punches and a sheet receiving slot transverse of said slots to enable said sheet to receive punch data in horizontal alignment with said printed data.

3. In a combined printing and punching machine in which a plurality of keys are provided and control the differential setting of a plurality of printing bars to print the data on a horizontal line on a sheet, said sheet being line spaced by the customary line spacing means, the combination of a plurality of punching bars differentially positioned under control of said keys, coded punch selecting means carried by each of

said bars, a group of four punches for each bar and at equidistant corners of an area equivalent to the area of each printed digit, said groups of punches arranged horizontally and aligned with the printing line and selected for operation by said coded punch selecting means, and a punch die provided with a slot to receive said sheet and other slots to receive said punches to thereby punch data in horizontal alignment with said printed data, and means to cause said coded punch selecting means to project selected punches to effect the perforating operation.

4. In an apparatus of the class described, four reciprocable punches arranged at four code positions which are at four equidistant corners, means for slidably mounting the set of four punches for each order, a perforated die cooperating with said punches, a differentially positioned bar for each order and each carrying a plate having punch operating projections arranged according to the code to select for operation certain punches according to the differential position of said bar, and means for operating said plate when said bar has been differentially positioned to project selected punches into said die to effect a record perforating operation.

5. In a punching machine provided with a plurality of banks of keys, a plurality of movable stop bars, one for each bank of keys and each having differentially disposed stop projections engageable by the depressed keys of the correlated bank to control the differential stopping of said stop bars, the combination of a plurality of differentially set punch selecting bars, means for moving said bars, electrical means for stopping said bars, a plurality of timing switches coordinated with said stop bars and movable synchronously with said punch selecting means to follow the movement of said stop bars, each of said stop bars causing, when stopped, the closure of said timing switches to energize said electrical means to stop the movement of said punch selecting bars at a digit position corresponding to the digit position of said stop bar.

6. In a punching machine provided with a plurality of banks of keys, a plurality of movable stop bars, one for each bank and each having differentially disposed stop projections engageable by the depressed keys of the correlated bank to differentially set said stop bars, the combination of a plurality of differentially set punch selecting bars, means for moving said bars, electrical means for stopping said bars, a plurality of timing switches coordinated with said stop bars, means operated by said moving means to move said timing switches synchronously with said punch selecting bars to follow the movement of said stop bars, each of said stop bars causing, when stopped, the closure of said timing switches to energize said electrical means to stop the movement of said punch selecting bar at a digit position corresponding to the digit position of said stop bar.

7. In a punching machine provided with a plurality of banks of keys, a plurality of movable stop bars, one for each bank of keys, and each having differentially disposed stop projections engageable by the depressed keys of the correlated bank to differentially set said stop bars, the combination of a plurality of differentially set punch selecting bars, electrical means for stopping said bars, a plurality of timing switches coordinated with said stop bars, common means to move said bars and said timing switches synchronously with said punch selecting bars to cause the latter to

follow the movement of said stop bars and beyond, and means carried by each of said stop bars for causing, when stopped and as said timing switch moves beyond the closure of said timing switches, the energization of said electrical means to stop the movement of said punch selecting bar at a digit position corresponding to the digit position of said stop bar.

8. In a punching machine provided with a plurality of banks of keys, a plurality of movable stop bars, one for each bank of keys and each having differentially disposed stop projections engageable by the depressed keys of the correlated bank to differentially set said stop bars, the combination of a plurality of differentially set punch bars, coded punch selecting means carried by said bars, means for moving said bars, electrical means for stopping said bars, a plurality of timing switches coordinated with said stop bars and movable synchronously with said punch bars to follow the movement of said stop bars, means carried by each of said stop bars for causing, when stopped, the closure of said timing switches to energize said electrical means to stop the movement of said punch selecting bar at a digit position corresponding to the digit position of said stop bar, and means to operate said coded punch selecting means to effect the movement of selected punches dependent upon the digit position of said punch bar.

9. In a punching machine, the combination of a plurality of ordered punch members having digit punching positions 1-9 and a 0 digit punching position, means for setting said punch members to selected digit punching positions 1-9 and in the absence of such digit positions to set punch members of all orders to 0 digit punching position, means normally operative to reset each punch member from said 0 digit punching position to a blank punching position, and means controlled by a punch member of highest significant digit order to render said last named means ineffective in its operation for digit punching orders to the left of said significant digit order to enable such members to be set to 0 punching positions to represent intermediate zeros.

10. In a punching machine, the combination of a plurality of ordered punch members having digit punching positions 1-9 and a 0 digit punching position, means for setting said punch members to selected digit punching positions 1-9 and in the absence of such digit positions to normally set punch members of all orders to 0 digit punching positions, a plurality of means, one for each order normally operative to reset the related punch member from said 0 digit punching position to a blank punching position, and means controlled by a punch member of highest significant digit order to render each of said last named means of lower orders ineffective in its operation to enable such lower order members to be set to 0 punching positions to represent intermediate zeros.

11. In a punching machine, the combination of a plurality of ordered punch members having digit punching positions 1-9 and a 0 digit punching position, means for setting said punch members to selected digit punching positions 1-9 and in the absence of such digit positions to normally set punch members of all orders to 0 digit punching positions, a plurality of means, one for each order, normally operative to reset each punch member from said 0 digit punching position to a blank punching position, said means having overlapping connections to cause said means of

higher order to operate one or more of said means of lower order, and means controlled by a punch member of highest significant digit order to render through said overlapping connections each of said plurality of means of orders to the left of said significant digit order ineffective to reset related punch members to zero to enable related punch members to be set to 0 punching positions to represent intermediate zeros.

12. In a punching machine, the combination of a plurality of ordered punch members having digit punching positions 1-9 and a 0 digit punching position, means for setting said punch members to selected digit punching positions 1-9 and in the absence of such digit positions to set punch members of all orders to 0 digit punching positions, a plurality of rockable members, cutout arms each engageable with a related rockable member to normally reset the related punch member from said 0 digit punching position to a blank punching position, and means controlled by a punch member of highest significant digit order to position the rockable member of that order and all lower orders out of the path of the related cutout arms to enable punch members of such orders to be set to 0 punching positions to represent intermediate zeros.

13. In a punching machine, the combination of a symbol printing bar settable prior to an operation of the machine to symbol printing positions representing auxiliary machine functions, a plurality of relays, electrical means controlled by said symbol printing bar to select a relay for energization according to its symbol printing position, a symbol punching member, means to position said member, electrical stop means to stop the position of said member, and differential electrical timing means controlled by said relays and rendered operative by an operation of the machine to energize said stop means to stop the symbol punching member at a symbol punching position corresponding to the symbol to be printed.

14. In a punching machine, the combination of a symbol printing bar settable prior to an operation of the machine to symbol printing positions representing auxiliary machine functions, a plurality of relays, electrical means controlled by said symbol printing bar to select a relay for energization according to its symbol printing position, a symbol punching member, means to position said member, electrical means normally locking said member against movement, electrical stop means to stop the position of said member, differential electrical timing means controlled by said relays and rendered operative by an operation of the machine to energize said stop means to stop the symbol punching member at a symbol punching position corresponding to the symbol to be printed, and circuit closing means to energize said electrical locking means to unlock said member prior to the operation of said electrical timing means.

15. In a punching machine, the combination of a symbol printing bar settable prior to an operation of the machine to symbol printing

positions representing auxiliary machine functions, a plurality of relays, electrical means controlled by said symbol printing bar to select a relay for energization according to its symbol printing position, a symbol punching member, means to position said member, electrical means normally locking said member against movement, electrical stop means to stop the position of said member, differential electrical timing means controlled by said relays and rendered operative by an operation of the machine to energize said stop means to stop the symbol punching member at a symbol punching position corresponding to the symbol to be printed, and a main circuit closure closed by an operation of the machine to concurrently close the circuit to a selected relay and energize said electrical locking means to unlock said member prior to the operation of said differential electrical timing means.

16. In a punching machine, the combination of a symbol printing bar settable prior to an operation of the machine to symbol printing positions representing auxiliary machine functions, a plurality of relays, electrical means controlled by said symbol printing bar to select a relay for energization according to its symbol printing position, a symbol punching member, means to position said member, electrical means normally locking said member against movement, electrical stop means to stop the position of said member, differential electrical timing means controlled by said relays and rendered operative by an operation of the machine to energize said stop means to stop the symbol punching member at a symbol punching position corresponding to the symbol to be printed, and a main circuit closure closed by at a near point in the operation of the machine to concurrently close the circuit to a selected relay and energize said electrical locking means to unlock said member and to render said differential electrical timing means operative during the subsequent operation of the machine.
